DESIGN FOR A SPOON OR SIMILAR ARTICLE OF TABLEWARE

Arthur I. Meyer, New York, N. Y.

Application November 7, 1947, Serial No. 142,370

Term of patent 14 years

(Cl. D54—12)

To all whom it may concern:

Be it known that I, Arthur I. Meyer, a citizen of the United States, and a resident of the city, county, and State of New York, have invented a new, original, and ornamental Design for a Spoon or Similar Article of Tableware, of which the following is a specification, reference being had to the accompanying drawings, forming part thereof and in which:

Fig. 1 is a front elevational view of a spoon showing my new design, the essential features of which reside in the handle shown in full lines, it being understood that the design may be adapted to use on knives, forks and similar articles of tableware without departing from the spirit of the invention;

Fig. 2 is a side elevational view thereof; and

Fig. 3 is a rear elevational view of the same.

I claim:

The ornamental design for a spoon or similar article of tableware, substantially as shown and described.

ARTHUR I. MEYER.
